DICTATING MACHINE

Manfred J. Johnson and Victor L. Frykman,
Bridgeport, Conn., assignors to Dictaphone
Corporation, New York, N. Y., a corporation of
New York

Application March 15, 1929, Serial No. 347,211
Renewed December 15, 1932

21 Claims. (Cl. 274—17)

This invention relates generally to dictating machines, and more particularly to a warning device for a dictating machine for indicating to the operator the operating condition of the machine under certain circumstances.

It is an object of this invention to provide means for warning the operator when the mandrel starting control is actuated with the stylus or sound-box control means in certain positions.

10 Other objects and advantages of the invention will appear hereinafter.

Frequently it happens that after the operator of a dictating machine has moved the stylus control to the neutral or to the reproducing position, 15 for example prior to placing a record-tablet on the mandrel or to listening to matter recorded on a record-tablet, the operator will actuate the starting mechanism and begin to dictate without noticing that the machine is not in condition for recording speech. The operator may continue to dictate for some time before becoming aware of the fact that the machine is not recording, and then will be under the necessity of repeating the dictated matter, after having 25 shifted the stylus control to the recording position.

According to this invention means are provided for giving a warning to the operator when the mandrel starting means is actuated with the 30 stylus control in other than the recording position. Preferably, the warning is given while the mandrel starting means is being actuated, and before the mandrel begins to rotate, and preferably the warning ceases before mandrel rotation 35 begins, so that in case the operator desires to listen to recorded matter there will be no interruption or interference by the warning means.

For a further disclosure of the invention, reference may be had to the following description 40 and to the accompanying drawings showing one embodiment of the invention selected merely for purposes of illustration, and in which:

Fig. 1 is a view, partly in elevation and partly in section, from the right hand end of a dictating machine;

Fig. 2 is a rear elevation of a portion of the machine shown in Fig. 1;

Fig. 3 is a view corresponding to Fig. 1, showing the mechanism in different operating condition, and showing certain features of the construction in more detail; and

Fig. 4 is a rear elevation of the machine in the operating condition shown in Fig. 3.

Referring to the drawings, a base plate 5 has, 55 near the left hand end of the machine, an upwardly projecting housing 6 and standard 9. Referring to Figs. 3 and 4, the housing 6 and standard 9 are provided with suitable bearings (not shown) for rotatably supporting one end of a mandrel shaft 10. The free end of the mandrel

shaft 10 carries a mandrel 7, upon which a record-tablet 8 may be slidably positioned.

Referring to Fig. 4, slidably mounted upon the mandrel shaft 10 within the housing 6 is a collar 11, which has an outer annular groove 12. The 65 collar 11 is connected to rotate with the shaft 10 by means of a pin or screw 13 set in the collar and extending through a slot in the shaft 10.

The pin 13 also passes through an opening in one end of a rod 14 which is slidably mounted in 70 an axial bore in the supported end of the shaft 10. This pin connection between the sleeve 11 and the rod 14 is such that the sleeve and the rod will rotate with the shaft 10, but may slide relative thereto within the limits of the length of the slot 75 through which the pin 13 passes.

The other end of the rod 14 extends outwardly beyond the end of the shaft 10, through the standard 9, and has a clutch disc 15 on its outer end. The clutch disc 15 is provided on its inner 80 face with a tooth which is adapted, when the rod and disc are moved to the left, to engage one of a plurality of clutch teeth on the hub 16 of a pulley wheel 17. The pulley wheel 17 is rotatably supported in suitable bearings in the standard 9, and will be connected by a belt, (not shown) with any suitable driving means, for example an electric motor connected to any suitable source of power in a well known manner by means of a switch which may be opened by removing a mouthpiece 90 from a movable support and closed when said mouthpiece is returned to its support. Such switch and control mechanism may be of the type disclosed in Patent No. 1,188,728.

With the sleeve 11 and the rod 14 in the positions shown in Fig. 4, the mandrel 7 is disconnected from the driving means. When the sleeve 11 is moved to the left, thereby causing the clutch disc 15 to engage the pulley hub 16, the mandrel may be driven by the driving means.

Referring to Figs. 3 and 4, the annular groove 12 in the sleeve 11 is slidably engaged at substantially diametrically opposite points by two pins forming a part of a clutch shifting yoke 18. The clutch shifting yoke 18 is fastened to the vertical arm of an angular lever 19, which is pivotally mounted on an inner wall of the housing 6. The horizontal arm of the lever 19 has at its outer end a turned over shelf-like portion 19'. Preferably, resilient means, (not shown) such as a spring is connected between the lever 19 and the housing 6 or the base plate 5, normally to maintain the sleeve 11 in the position shown in Fig. 4, with the clutch members disengaged.

As may best be seen in Fig. 3, the upper surface of the shelf-like portion 19' of the lever 19 is engaged by the horizontal arm of a second angular lever 20, which is pivotally mounted on an inner wall of the housing 6. The vertically extending arm of the lever 20 engages at its upper end 115

120

with the terminal of a Bowden wire mechanism in such a manner that actuation of the Bowden wire will turn the lever 20 about its pivot to depress the horizontal arm of the lever 19, thereby moving the sleeve 11 and rod 14 to the left, and causing the mandrel clutch members to engage.

Extending longitudinally of the machine, and supported at their ends by the standard 9 and a similar standard, (not shown) near the other ends 10 of the base plate, are the upper and lower carriage supporting and guiding members 21 and 22. Slidably mounted upon the members 21 and 22 is a sound-box carriage 23.

15 Referring to Figs. 1 and 2, the upper member 21
preferably is in the form of a tube having a lon-
gitudinal opening along its under side. Within
the member 21 is a feed screw 24, which is con-
nected in any suitable manner, (not shown) with
the mandrel shaft 10, so as to rotate when the
20 mandrel rotates. The feed screw 24 may be en-
gaged by a feed nut 25 on the carriage 23. When
the feed nut is in engagement with the feed screw,
and the feed screw is rotating, the carriage 23
will be moved along the machine. For a further
25 disclosure of this construction, which forms no
part of the present invention, reference may be
had to United States Letters Patent of T. H. Mac-
donald, No. 1,100,024, June 16, 1914.

30 Still referring to Figs. 1 and 3, surrounding the carriage guiding member 21 is a collar 26 having an upwardly projecting, manually operable, stylus control lever 27. The lower edge of the collar 26 is connected by means of a pin 28 to one end of a forwardly extending link 29. The forward end of the link 29 has a hook and slot connection 30 with a tube 31 slidably mounted in and forming part of a sound-box casing 32 which is mounted on the front portion of the carriage 23.

40 As is best shown in Fig. 1, a forwardly extending, reduced tubular portion of the sound-box casing is connected by means of an elbow 33 and a flexible tube 34 to a handle 35 which carries a mouth-piece 36. The handle 35 is provided with a control button 37 connected with one end of a Bowden wire 38. The Bowden wire preferably passes through the flexible tube 34, and at its distant end is connected to the housing 6. The arrangement is such that depression of the button 37 actuates the Bowden wire, so as to cause the plunger portion of the wire at the end connected to the housing 6 to turn the lever 20 and thereby cause engagement of the mandrel clutch members in the manner hereinbefore described.

Thus it is seen that the button 37 through the Bowden wire, acts as a stop-and-start control for the mandrel. For a further disclosure of the Bowden wire stop-and-start control, reference may be had to United States Letters Patent of C. E. Woods, No. 1,203,088, October 31, 1916.

65 Referring to Fig. 3, telescopically mounted with in the forwardly extending reduced tubular por-
tion of the sound-box casing 32 is one end of a tapered tubular member 39 which is connected with the tube 31 so as to be moved therewith. The inner end of the tubular member 39 has a ball and socket connection with one end of a sound-box tube 40, which carries at its other end a sound-box 41. The tubular members 40 and 39, the elbow 33, the tube 34, and the handle 35 provide for the transmission of sound between the sound-box 41 and the mouthpiece 36. The sound-box 41 has a diaphragm carrying a record-
ing stylus 42 and a reproducing stylus 43.

With the control lever 27 in the forward or

recording position, shown in full lines in Fig. 3, the link 29 has caused the tubes 31, 39 and 40 to be moved to the rear to bring the recording stylus 42 into engagement with the record-tablet 8. When the parts have been so moved, the

8. When the control lever is in the rear or reproducing position, as shown in full lines in Fig. 1, the tubes 31 and 40 are in a forward position, which brings the reproducing stylus into engagement with the record-tablet 8. When the control lever is in the intermediate or neutral position, shown in dotted lines in Figs. 1 and 3, both stylii will be lifted from the record surface by the engagement of a lug 44 on the lower side of the sound-box tube 40 with a finger 45 adjustably fastened on the casing 32. 90

fastened on the casting 32. 90

For further details of the sound-box construction and control means reference may be had to Macdonald Patent No. 1,100,024, previously referred to, and to United States patents to Scully, No. 1,093,732, April 21, 1914, and Bodine et al. 95 No. 1,606,744, November 16, 1926.

In the arrangement thus far described the mandrel stop-and-start control means may be actuated irrespective of the operating condition of the machine. According to this invention, 100 means are provided, associated with the mandrel stop-and-start control, for warning the operator when the control is actuated to start the mandrel with the stylus control in other than recording position.

Where the stop-and-start control includes a Bowden wire, as in the illustrated embodiment, means conveniently may be associated with the Bowden wire and the stylus control, so that actuation of the Bowden wire when the stylus control is in other than recording position is effective to warn the operator that the dictating machine is not in condition for recording speech. This warning may comprise either a visual indication, a sound indication, or both. In the embodiment disclosed herein, means are provided for causing a striker to impinge once on the same bell which is used to warn of the approach of the carriage toward the end of a record-tablet, said means being rendered ineffective to actuate the striker when the stylus control is in recording position.

Referring to Figs. 2 and 4, slidably mounted on the back side of the downwardly extending part of the carriage 23 is a plate 50. The plate 50 is free to move in a vertical plane, and is held in position by two screws extending through slots in the plate and engaging openings in the carriage. Connected to the plate 50 is one end of a tension spring 51, the other end of the spring being connected to a pin set in the carriage 23. The spring 51 normally tends to move the plate 50 upwardly.

The upper end of the plate 50 has two outwardly turned ears which support a roller 52. As may better be seen in Figs. 1 and 135 3, under the tension of the spring 51, the roller 52 and the plate 50 are pressed upwardly against the lower rear edge of the collar 26, which carries the upwardly projecting stylus control lever 27. The collar 26 has on its lower rear edge a lug or cam 53. When the stylus control lever 27 is in the forward or recording position, as shown in full lines in Fig. 3, the lug 53 is turned substantially out of engagement with the roller 52, and the plate 50 is moved upwardly by the spring 51 until the plate 50 occupies its uppermost position.

However, when the stylus control lever 26 is moved backwardly to the neutral or to the reproducing position, (see Fig. 1) the collar 26 is

turned, causing the lug 53 to engage the roller 52 and depress the roller and plate 50 against the tension of the spring 51.

As may best be seen in Figs. 2 and 4, the plate 50 is provided intermediate its ends with an outwardly turned ear 54. The ear 54 is adapted, when the plate 50 is in the raised position, shown in Figs. 3 and 4, to engage the lower side of and lift a rod 55. The rod 55 is loosely mounted at its ends in two forwardly and downwardly inclined slots in two outwardly turned ears of a plate 56 secured to the back side of the carriage 23. When the plate 50 is in the lowered position shown in Figs. 1 and 2 the ear 54 is below the bottoms of the inclined slots, and the rod 55 drops to the bottoms of the slots due to gravity. If desired, yielding means could be connected to the rod 55 normally tending to draw the rod downwardly.

Referring to Figs. 2 and 4, secured to the right hand end of the rod 55 is a downwardly depending bell striker 57. The striker 57 normally is drawn toward the back of the machine, i. e. toward the reader in Figs. 2 and 4, by means such as the spiral tension spring 58, which is secured at its ends to the striker and to the carriage. The spring normally tends to turn the rod 55 in a counter-clockwise direction as viewed in Figs. 1 and 3. This turning movement of the rod 55 may be limited by the engagement of the striker 57 with a bell 59 mounted on the carriage. Secured to the left hand end of the rod 55 is a small downwardly depending cam lever 60.

It will be seen from the foregoing description that if the rod 55 is turned slightly in a clockwise direction, as viewed in Figs. 1 and 3, against the tension of the spring 58, and is then released, the spring 58 will draw the striker to the rear, causing it to impinge on the bell 59.

Referring to Figs. 2 and 4, the plate 56 which supports the rod 55 has at its left edge an inwardly turned ledge to which is secured a recessed block 61. As may best be seen in Figs. 1 and 3, the Bowden wire 38 passes through the block 61. The outer conduit member of the Bowden wire is broken, and the two ends of the outer conduit member are secured in the walls of the block 61 where the wire enters and leaves the block. The interior wire member 62 of the Bowden wire passes through the recess in the block 61, and has secured thereto, near the rear wall of the recess, a collar 64. Pivotal mounted in the recess and lying along side the interior member 62 between the collar 64 and the forward wall of the recess is a crank 65. The crank 65 is adapted to be turned in a counter-clockwise direction by the collar 64 when the inner member of the Bowden wire is moved or drawn forward. Surrounding the interior member 62 within the block recess and between the crank 65 and the forward wall of the recess is a spiral spring 63 normally tending to turn the crank in a clockwise direction.

By referring to Fig. 1 it will be seen that when the stylus control lever is in either reproducing or neutral position, the rod 55 is in its lowermost position. Under these conditions, actuation of the Bowden wire control 37 in the well known manner, thereby drawing the interior member through the block 61 and turning the crank 65 in a counter-clockwise direction, will cause the crank 65 to trip the cam lever 60, turning and subsequently releasing the rod 55, and causing the striker 57 to impinge on the bell 59 in the manner hereinbefore described. Thus it is seen that actuation of the control to start the mandrel will

cause a warning signal to be given when the stylus control is in neutral or reproducing position.

On the other hand, when the stylus control is in recording position, as shown in Fig. 3, the rod 55 has been lifted by the plate 50 and spring 51 so that the cam lever 60 is out of range of and will not be operated by turning movement of the crank 65. With the stylus control in recording position, actuation of the Bowden wire does not cause a warning signal to be given.

The warning signal is given as an incident to actuation of the mandrel starting control, and the warning signal indicates to the operator that the machine is not in condition for recording. However, the warning signal preferably ceases before the mandrel begins to rotate, so that if the operator is listening to matter already recorded the signal will in no manner interfere with this operation.

On the lowermost portion of the carriage frame is pivotally mounted a second bell striker 66 which normally is held in the position shown in the drawings by means of a spiral tension spring 67. The striker 66 has a downwardly depending arm, the lower end of which is adapted, when the carriage approaches the end of a record-tablet, to engage a stop 68, (Fig. 2) mounted on the base plate 5. As the carriage continues to move, the stop 68 causes the striker 66 to be turned and tripped, whereupon the spring 67 causes the striker to impinge on the bell 59, thereby giving a warning that the carriage is near the end of the record-tablet.

It will be seen that the invention provides a simple mechanism for accomplishing the stated objects.

The invention may be variously modified and embodied within the scope of the appended claims.

We claim:

1. The combination in a dictating machine of a record support, control means for controlling the operation of said record support, a stylus, control means for moving said stylus into and out of record-engaging position, and signal means for giving a positive warning when said first control means is actuated with the second control means in a given position.

2. The combination in a dictating machine of a record support, control means for controlling the operation of said record support, a stylus, control means for moving said stylus into and out of record-engaging position, and signal means for giving a positive warning when said first control means is actuated with the stylus out of record-engaging position.

3. The combination in a dictating machine of a record support, a stylus control having recording, neutral and reproducing positions, control means for controlling the rotation of said record support, and signal means for giving a positive warning upon actuation of said control means when said stylus control is in a given position.

4. The combination in a dictating machine of a record support, a stylus control having recording, neutral and reproducing positions, control means for controlling the rotation of said record support, and signal means for giving a positive warning upon actuation of said control means when said stylus control is in other than recording position.

5. The combination in a dictating machine of a record support, a stylus control having recording, neutral and reproducing positions, control means for controlling the rotation of said record support, and signal means for giving a positive

- warning upon actuation of said control means when said stylus control is in reproducing position.
6. The combination in a dictating machine of a record support, a stylus control having recording, neutral and reproducing positions, control means for controlling the rotation of said record support, and signal means for giving a positive warning upon actuation of said control means when said stylus control is in neutral position.
7. The combination in a dictating machine of a record support, means for controlling the rotation of said record support, a stylus having alternative positions, a stylus control, and signal means for giving a positive warning upon actuation of said rotation controlling means when said stylus control is set to hold said stylus in certain of said alternative positions.
8. The combination in a dictating machine of a record support, means for controlling the rotation of said record support, a stylus having alternative positions, a stylus control having a recording position, and signal means for giving a positive warning upon actuation of said rotation controlling means when said stylus control is in other than recording position.
9. The combination in a dictating machine of a record support, means for controlling the rotation of said record support, a stylus having alternative positions, a stylus control having a reproducing position, and signal means for giving a positive warning upon actuation of said rotation controlling means when said stylus control is in reproducing position.
10. The combination in a dictating machine of a record support, means for controlling the rotation of said record support, a stylus having alternative positions, a stylus control having a neutral position, and signal means for giving a positive warning upon actuation of said rotation controlling means when said stylus control is in neutral position.
11. The combination in a dictating machine of a record support, control means for controlling the rotation of said record support, a stylus control having recording and non-recording positions, and signal means operatively associated with said control means and said stylus control for giving a positive warning signal upon actuation of the control means with the stylus control in non-recording position.
12. The combination in a dictating machine of a record support, a Bowden wire for controlling the rotation of said record support, a stylus control having alternative positions, signal means, and means for causing said signal means to give a warning signal upon actuation of the Bowden wire when the stylus control is in certain of said alternative positions.
13. The combination in a dictating machine of a record support, a Bowden wire for controlling the rotation of said record support, a stylus control having recording and non-recording positions, signal means, and means for causing said signal means to give a warning signal upon actuation of the Bowden wire when the stylus control is in non-recording position.
14. The combination in a dictating machine of a record support, means comprising a clutch for driving said record support, means for controlling the driving of said record support by said driving means, signal means, and means associated with said controlling means for causing said signal means to give a positive warning signal as an incident to the actuation of said controlling means and independently of the operation of said clutch.
15. The combination in a dictating machine of a record support, driving means for said record support, signal means, control means, means associated with said control means for causing said signal means to give a warning upon initial actuation of the control means, and other means associated with said control means to cause the driving means to rotate the record support upon a further actuation of said control means.
16. The combination in a dictating machine of a record support, driving means for said record support, signal means, control means, means associated with said control means for causing said signal means to give a warning upon initial actuation of the control means, other means associated with said control means to cause the driving means to rotate the record support upon a further actuation of said control means, and means for rendering said warning causing means ineffective to cause said signal means to give a warning.
17. The combination in a dictating machine of a record support, driving means for said support, a Bowden-wire for controlling the operation of said driving means, a bell, a striker suitably mounted to ring said bell, and means responsive to movement of said Bowden-wire for actuating said striker.
18. The combination in a dictating machine of a record support, driving means for said support, a Bowden-wire for controlling the operation of said driving means, a bell, a striker suitably mounted to ring said bell, means responsive to movement of said Bowden-wire for actuating said striker, stylus control means, and means responsive to movement of said stylus control means to a predetermined position for preventing actuation of said striker.
19. In a machine operable to record or reproduce dictation, in combination, means for starting the machine, mechanism for recording and reproducing dictation having recording, neutral and reproducing positions, a warning device adapted to be activated to draw attention to the condition of said mechanism as to position, and means responsive to actuation of said means for starting the machine for causing activation of said warning device if said mechanism is in reproducing position.
20. In a machine operable to record or reproduce dictation, in combination, means for starting the machine, mechanism for recording and reproducing dictation having recording, neutral and reproducing positions, a warning device adapted to be activated to draw attention to the condition of said mechanism as to position, and means responsive to actuation of said means for starting the machine for causing activation of said warning device if said mechanism is in neutral position.
21. In a dictating machine, in combination, a rotatable record-support, a record-support start-and-stop control, a sound-box having elements movable to selected positions, a warning device, and means for rendering said warning device effective upon actuation of said start-and-stop control but before the latter becomes effective to cause rotation of said record-support when said sound-box elements occupy other than a certain selected position.

MANFRED J. JOHNSON.
VICTOR L. FRYKMAN.
